COTTON GIN

Thaddeus S. Grimes, Columbus, Ga., assignor to
 Lummus Cotton Gin Company, Columbus, Ga.,
 a corporation of Georgia

Application May 14, 1936, Serial No. 79,770

12 Claims. (Cl. 18—59)

This invention relates to cotton gins of that type in which an air blast is used to remove the lint from the gin saws.

The main object of this invention is to provide a gin of the class described with means for removing from the gin, such motes as are thrown off the saws by centrifugal force before they arrive at the air blast nozzle.

Another object of the invention is to provide a gin of the class described with a partition to prevent motes thrown off the saws by centrifugal force from falling into the lint flue, and with means for removing by air blast, such motes as are carried by the saws past such partition.

Another object of the invention is to provide a gin of the class described with a partition and carrying means so located to each other as to prevent any accumulation of motes on top edge of partition.

Other objects of the invention will become apparent as the detailed description thereof proceeds.

The single figure of the drawing is a central vertical section through a cotton gin having my invention applied thereto.

The drawing shows a saw cylinder 1 of usual construction having saws 2 fixed to the shaft 3 which is journaled at its opposite ends within the housing 4 of the gin. Seed cotton fed to the saws within the ginning roll box A is ginned in the usual manner. The lint cotton is separated or pulled off the seed as the saws pass through the closely spaced ginning ribs 4'. The lint adhering to the saws is carried down to the air blast 35 where it is blown off of the saws in to the lint flue 18. A large quantity of motes and trash are thrown off centrifugally from the saws into the mote removing chamber 5, but such motes and trash as are not thrown off into chamber 5 are again acted upon and thrown out of the lint cotton by the air blast means as disclosed in my U. S. Patent No. 1,241,466, dated September 25, 1917. (See last paragraph, page 2, of this patent; also lines 29 to 36 on page 3.)

The bottom of the chamber 5 is formed by a substantially horizontal trough 6 having a partition 7 extending lengthwise therein. The partition forms a support for the upper strand 8 of an endless conveyor belt, the lower strand 9 thereof being supported by bottom of the trough 6.

The trough 6 with its conveyor belt is arranged slightly above the horizontal plane passing through the axis of the saw cylinder, and with one edge thereof quite close to the periphery of said cylinder. A rear wall 10 of the chamber 5

has its upper edge suitably secured to a transverse bar 11 forming part of the framework of the gin; and, is inclined to the horizontal at such an angle as to deflect the motes upwardly in the general direction of the bar 11. An auxiliary deflector plate 12 fixed to the edge of the bar 11 serves as a baffle to ensure that motes deflected by the inclined wall 10 shall fall on the conveyor belt and not on the rotating saw cylinder.

The side wall 13 of the trough 6 forms, in effect, 10 a division board between the saws and the mote conveying belt. The belt conveying means prevents any accumulation of motes on the top edge of the division plate 13 due to the wiping effect of the continuously moving belt closely located to 15 the top edge of it.

The small space occupied vertically by the belt conveyor, permits the effective use of an air blast mote remover in such position that the inlet to the lint flue is so nearly vertical that a large 20 amount of the moting can still be effected by air blast mechanism such as is disclosed in my U. S. Patent No. 1,241,466, September 25, 1917.

The framework of the gin supports an air box 14, which as usual, is arranged lengthwise of the 25 saw cylinder or cylinders; and is connected to an air duct 15 which terminates at the bottom of the conveyor trough 6. A deflector plate 16 extends downwardly from the bottom of trough 6 and terminates at a slight distance above the 30 horizontal diameter plane of the saw cylinder.

The lower wall 17 of the air duct 15 is bent at its upper edge to form with the plate 16, a nozzle for directing the air against the saw cylinder so as to strip the saw teeth of all lint, and direct 35 the lint into the lint flue 18. The various air deflecting surfaces of this nozzle are arranged substantially as disclosed in my said U. S. Patent No. 1,241,466, and, therefore, need not be described in detail herein.

In the structure described, it will be apparent that the heavier motes thrown off the saws by centrifugal force are collected in the chamber 5 and continuously removed by the strand 8 of the belt conveyor, thereby eliminating all possibility of motes accumulating on the division board in quantities sufficient to cause them to fall back on the saws. In addition to this feature of overhead moting, there is retained all the efficiency of the air blast underneath moting disclosed in 50 my aforesaid U. S. patent.

The arrangement shown nearly doubles the moting efficiency of the gin. Since only a portion of the motes pass below the deflector plate 16, it will be obvious that the usual proportion of 55

them will be thrown away by the airblast from the mouth of the lint flue.

What I claim is:

- of supply of air under pressure, a conduit connected to said source and having a nozzle located substantially in a horizontal plane passing through the axis of said cylinder for directing air against the saw teeth of said cylinder at an angle to the horizontal plane, a lint flue directly below said nozzle and having a substantially vertical inlet opening adjacent the periphery of said cylinder; a dead air chamber in communication with the upper part of said cylinder, an endless substantially horizontal belt conveyor in said chamber directly above said nozzle and horizontal plane, deflecting plates in said chamber for directing particles thrown from said cylinder onto said belt, and a division plate mounted between said cylinder and conveyor belt and having its upper edge extending slightly above and close to the edge of said belt.
- 5 10 15 20 25 30
- the upper part of said cylinder, an endless substantially horizontal belt conveyor in said chamber directly above said nozzle and horizontal plane, a deflecting plate arranged at an angle to said belt conveyor at the edge thereof remote from the said cylinder, a second deflecting plate arranged above the edge of the conveyor adjacent the saw cylinder, and a division plate mounted between said cylinder and conveyor belt and having its upper edge extending slightly above and close to the edge of said belt.
11. In a cotton gin, a gin saw cylinder, a source of supply of air under pressure, a conduit connected to said source and having a nozzle located substantially in a horizontal plane passing through the axis of said cylinder for directing air against the saw teeth of said cylinder at an angle to the horizontal plane, a lint flue directly below said nozzle and having a substantially vertical inlet opening adjacent the periphery of said cylinder; a dead air chamber in communication with the upper part of said cylinder, an endless substantially horizontal belt conveyor in said chamber directly above said nozzle and horizontal plane, means for preventing the return to said cylinder of particles thrown therefrom into said chamber, and a division plate mounted between said cylinder and conveyor belt and having its upper edge extending slightly above and close to the edge of said belt.
12. In a cotton gin, a gin saw cylinder, a source of supply of air under pressure, a conduit connected to said source and having a nozzle located substantially in a horizontal plane passing through the axis of said cylinder for directing air against the saw teeth of said cylinder at an angle to the horizontal plane, a lint flue directly below said nozzle and having a substantially vertical inlet opening adjacent the periphery of said cylinder; a dead air chamber in communication with the upper part of said cylinder, an endless substantially horizontal belt conveyor in said chamber directly above said nozzle and horizontal plane, a deflecting plate arranged at an angle to said belt conveyor at the edge thereof remote from the said cylinder, a second deflecting plate arranged above the edge of the conveyor adjacent the saw cylinder, and a division plate mounted between said cylinder and conveyor belt and having its upper edge extending slightly above and close to the edge of said belt.
